UNITED STATES PATENT OFFICE.

CHARLOTTE UEBEL, OF CHICAGO, ILLINOIS.

SHIRT.

SPECIFICATION forming part of Letters Patent No. 731,418, dated June 16, 1903.

Application filed April 23, 1903. Serial No. 153,910. (No model.)

To all whom it may concern:

Be it known that I, CHARLOTTE UEBEL, a citizen of the United States, residing at Chicago, Illinois, have invented a certain new and useful Improvement in Shirts, of which the following is a specification.

My invention relates to that class of shirts which are constructed with double bosoms and so designed that one bosom will overlap the other, completely covering it and presenting the outward appearance of an ordinary shirt. By means of this construction when a white or light-colored shirt is worn and the bosom becomes soiled, while the garment is otherwise practically clean, the under bosom may be adjusted to overlap the other, and thereby present a bosom that is immaculate.

The special object of the present invention is to provide a shirt of the kind stated of such construction that the neckband will not be of double thickness at the sides of the neckband, the presence of which would subject the wearer to considerable discomfort, and also to provide one in which the bosoms will be efficiently held smooth and fastened at points intermediate of their upper and lower ends without requiring the provision of a multiplicity of fastening devices and without requiring that the fastening devices be located in the bosom proper, which latter location is disadvantageous, especially when the shirt has a bosom intended to be starched.

To this end the invention consists in the peculiarities of construction hereinafter set forth, and particularly pointed out in the subjoined claim.

In the accompanying drawings, Figure 1 is a front view of a shirt embracing my improvements with both bosoms folded back. Fig. 2 is a similar view with the bosoms in place as worn, in this instance the right-hand one overlapping the left.

A designates the body of the shirt, having an opening in its front side to be covered by the bosoms hereinafter described and also preferably provided contiguous to the lower end of said opening with a tab a^2 , having a button c^3 or other securing means for the lower edges of the bosoms at the centers thereof.

50 B and B' designate the bosoms, one of which is sewed or otherwise suitably fixed permanently along its right-hand longitudi-

nal edge to the body A, while the other is similarly permanently fixed along its left-hand edge to said body. The other portions 55 of the bosom are free and provided with means by which they are adjustably secured.

a designates the neckband, a part of which is secured to the body of the shirt, and from which body portion it is prolonged at opposite sides to the free edges of the bosoms, as shown at a' . In the construction shown the neckband is divided in the back; but this is not essential, and in some instances it is desirable not to have the shirt open at the back.

A portion of the lower edges of the bosoms may, as shown, be permanently fixed to the shirt-body at opposite sides of the tab a^2 .

Provision is made for securing the free corners of the bosoms detachably to the shirt-body, and particular attention is called to the fact that the upper securing means, which holds both the upper edge of the bosom and the end of the neckband carried by said bosom, does not extend through the neckband, but is located beneath said band at the upper corners of the bosoms, as at b, and hence does not impose upon the wearer the discomfort which is experienced when the bosom 80 portions of the neckbands are secured to the body portions thereof at the sides of the neck. Moreover, to further conduce to the comfort of the wearer at the neck portion of the shirt the bosom portions of the neckband overlap 85 each other at the front only, each prolongation a' being tapered, as shown, so that the sides are of single thickness. The neckbands are joined by a collar-button b' at the center. Thus is provided a neat-fitting and convenient arrangement by which is obviated the discomfort attendant upon the doubling of the neckband at the sides of the neck and the securing of the ends thereof at said place by a button or otherwise, which will make it 95 uncomfortable to wear a collar over said fastenings.

In order that the bosoms may fit smoothly, securing means should be provided for their free longitudinal edges in other places than at the corners, and in order that this may be accomplished with a minimum number of fastening devices and without requiring the fastening devices to be in the bosoms proper the

free longitudinal edge of each bosom is provided with an extension-strip c and c' , respectively, which overlap the body of the shirt and are secured at b^2 and b^3 , respectively, removably to said body adjacent to the arm-holes. Each extension-strip c and c' is preferably tapered, as shown, from the corners thereof to the bottom corners of the bosoms, and its lower side preferably is longer than its upper side. The fastenings b^2 b^3 are double—that is, one upon the outside and one upon the inside of the body portion—so that each bosom may be securely held whether being used as the outside or inside bosom.

15 From the foregoing it will be seen that I have provided a shirt which when in use does not differ greatly in appearance from that of a one-bosom shirt, although it practically affords the wear of two one-bosom shirts. It is 20 obvious that shirts of this design may be made with a collar attached, which may be preferable in the case of woolen or heavy shirts or with detachable collars, which is more desirable in the case of starched shirts.

25 Having thus described my invention, what I believe to be new, and desire to secure by Letters Patent, is—

The herein-described shirt having a body formed with an opening at its front, two 30 bosoms one of which is fixedly secured to said body at one side of said opening and the other

fixedly secured to said body at the other side of said opening, said bosoms being arranged to overlap each other in front of said opening and with either bosom outermost, said 35 bosoms having free longitudinal edges each of which is provided with an extension of which one overlaps the body of the shirt at one side of the opening and the other overlaps the body of the shirt at the other side of 40 said opening, devices for securing said extensions to the body of the shirt said body having a tab at the lower end of said opening, securing means engaging said tab and the overlapped bosoms, a neckband a portion 45 of which is formed on the body of the shirt and the remaining portions of which constituting ends thereof are prolonged along the upper edges of the respective bosoms, fastening means for the overlapped portions of said 50 ends at the front of the shirt, and fastening means for the outermost ends of the neckband and the upper edges of the bosom, the latter fastening means engaging the body of the shirt below the portion of the neckband 55 on said body, all substantially as described and for the purposes set forth.

CHARLOTTE UEBEL.
